UNITED STATES PATENT OFFICE.

FOSTER MILLIKEN, OF NEW YORK, N. Y.

DESIGN FOR A FRAME FOR DRILLING-MACHINES.

SPECIFICATION forming part of Design No. 26,287, dated November 17, 1896.

Application filed September 28, 1896. Serial No. 607,258. Term of patent 3½ years.

To all whom it may concern:

Be it known that I, FOSTER MILLIKEN, a citizen of the United States, residing at New York city, in the county and State of New York, have invented and produced a new and original Design for a Frame for Drilling-Machines, of which the following is a specification, reference being had to the accompanying drawing, forming a part thereof, which 5 represents a perspective view of a frame embodying the features of my design.

The design consists of a cruciform base A, from each end of the longer member of which two columns 10 are projected upward, and 10 two central columns 11 are likewise projected upward from the shorter member of the base at one side of its junction with the longer member, while two other central columns 12 are carried upward from the shorter member 15 of the base at the opposite side of its connec-

tion with the longer member. The central columns 11 and 12 support a handle-bar 13, and the right-hand central columns are connected by horizontal columns 14 with the right-hand end columns 10, as are likewise 25 the left-hand central columns connected by horizontal columns 14 with the left-hand vertical columns 10. A support 15 for a seat 16 is mounted upon one pair of horizontal columns, while bearings 17 are placed upon the 30 two sets of central columns 11 and 12. The base A is shown as having roller-supports 18.

I claim—

The design for the drilling-machine frame herein shown and described.

FOSTER MILLIKEN.
